Claims priority, application Great Britain Feb. 17, 1953

1 Claim. (Cl. 330—8)

This invention relates to the switching of alternating currents. The object of the invention is the provision of a switching system using only magnetic cores, resistors, condensers and rectifiers. Such a system has an advantage over existing electromechanical systems and electronic systems using tubes in that the components have extremely long life. Durability can be further increased by embedding the magnetic components in materials such as synthetic resin.

The devices to be described are based on the second harmonic transformer and have been designed to be particularly suitable for the switching of voice frequencies in telephone exchange systems. However, it is to be clearly understood that the invention is not to be restricted to that application and that the principles to be disclosed could equally well be applied to the switching of alternating currents of other frequencies. Moreover, while the invention has been described with reference to a particular construction of second-harmonic transformer, any convenient construction may be employed.

The main feature of the invention comprises a magnetic switch-amplifier comprising a first second-harmonic transformer and a second second-harmonic transformer, means for applying a first alternating current to the primary winding of said first second-harmonic transformer, means for applying a direct current control signal to a first secondary winding of said first second-harmonic transformer, means for applying alternating current induced in a second secondary winding of said first second-harmonic transformer to the primary winding of said second second-harmonic transformer, means for applying an information-bearing signal of variable amplitude to a secondary winding of said second second-harmonic transformer and demodulating means for obtaining from the current in the primary winding of said second-harmonic transformer an information-bearing signal of variable amplitude.

This invention will be described with reference to the accompanying drawings in which:

Figs. 1 and 2 show respectively in perspective and in elevation a preferred construction for a magnetic amplifier;

Fig. 3 shows the electrical circuit of the magnetic amplifier of Figs. 1 and 2;

Fig. 4 is a curve relating to the circuit of Fig. 3;

Fig. 5 is an alternative circuit for a magnetic amplifier;

Fig. 6 is a switch amplifier useful in the construction of selector switches for voice frequency switching systems;

Figs. 7, 8, and 9 show schematically selector switches employing the switch amplifier of Fig. 6.

In the application of the invention which is to be described, alternating magnetic fluxes of high frequency are encountered which present problems not met with when the principles of the invention are applied to the switching of lower frequencies.

It may be shown that if a voltage E of frequency F

2

is applied to an iron cored winding so that a current I flows, then

$$EI = \frac{B_{\max}^2 V f \cdot 10^7}{4} \quad (1)$$

where $B_{\max}$ is the maximum flux density (at saturation), f is the permeability of the magnetic material and V is its volume. Suppose that the magnetic material employed were Permalloy "C" then

$$B_{\max} = 8,000$$

$$f = 1,000$$

Suppose also that the applied frequency was 100 kc./s. and that EI was 1 volt-amp., then substituting in (1) above it is found that

$$V = .00625 \text{ cc.}$$

It is therefore obvious that at frequencies such as 100 kc./s. the volume of the core-member of any magnetic device must be very small. The design of the devices to be described has been influenced by the need to minimize the amount of magnetic material used. However, in practice, design is aided by the fact that any volume of saturable magnetic material behaves as a smaller volume due to skin effects.

Referring to Figs. 1 and 2 a construction for a magnetic amplifier designed with these considerations in mind consists of four windings L_1 , L_2 , L_3 and L_4 . The windings L_3 and L_4 are wound on the bobbins 3 and 4 respectively. The windings L_1 and L_2 are both wound on a single bobbin 1. After the coils have been wound the bobbins are mounted on a tag-board 2.

After mounting, two lengths of tape of a saturable magnetic material are threaded spirally through the bobbins so as to form the two loops 5 and 6. The two loops then together constitute a three-limbed core, the three limbs being designated 7, 8 and 9.

Fig. 3 shows diagrammatically the component described with reference to Figs. 1 and 2, together with the associated circuits necessary for its functioning as a magnetic amplifier for voice frequencies.

The coils L_3 and L_4 wound on the outer bobbins 3 and 4 of Fig. 1 are connected in series to a source of carrier frequency at the terminals A_1 . A direct current bias is applied across the terminals B_0 . The considerations affecting the choice of the magnitude of this bias will be discussed later.

Now, it is well-known that if a sinusoidal voltage is applied to the primary of a transformer, of an amplitude sufficient to extend the hysteresis loop into the region of saturation, then the potential appearing on the secondary winding will possess the same frequency as the applied voltage, together with odd harmonics. As long as the hysteresis loop is symmetrical this will be the case, since the symmetry precludes the production of even harmonics. However, if a small direct-current flux is superimposed upon the alternating flux in the ferro-magnetic core of the transformer, then even harmonics will also appear in the secondary winding.

Referring again to Fig. 3 it will be seen that the two coils L_3 and L_4 are wound in the same sense so that the magnetic fluxes through the common member 8 of the three-limbed core, due respectively to the coils L_3 and L_4 are opposed. Thus the fundamental frequency and odd harmonics cancel, leaving only even harmonics, of which the second will predominate, in the secondary winding L .

The voice frequency to be amplified is applied across the terminals E_1 . It is necessary to insert the filter-section constituted by the inductance Z_1 and the condensers C_1 and C_1' to prevent the even harmonics induced in the coil L_1 appearing at the terminals E_1 . The resist-

ance R_1 is necessary for correct termination of the voice-frequency circuit.

The choice of the magnitude of the direct current bias applied across the terminals B_0 will now be considered. Fig. 4 shows the general shape of the graph of A.C. ampere-turns in the carrier circuit L_3-L_4 ($I_a N_a$) plotted against the total ampere-turns in the coils L_1 and L_2 ($I_o N_o$). As the value of the ampere-turns for the coil L_2 for example increases either positively or negatively (i.e. as the bias current in L_2 increases in either direction) the value of the ampere-turns in the carrier circuit increases slowly at first, then more quickly, and continues to increase steadily until a limiting value is reached either at S or S'. Thus the current due to the voice frequency signal in the coil L_1 causes an excursion along the characteristic about some point determined by the D.C. bias current in L_2 . By a suitable choice of a standing bias in the direct current winding L_2 the amplifier can be biased to work over a linear part of its characteristic, as for instance about the point X.

The output for the amplified voice frequency is at the terminals E_2 . The modulated carrier signal is demodulated by the rectifier r_2 . The low-pass filter section constituted by the inductance Z_2 and the condensers C_2 and C'_2 is designed to suppress the carrier frequency so as to prevent its appearing at the terminals E_2 .

In a particular practical case the coils L_1 and L_2 consisted of respectively 180 and 120 turns while L_3 and L_4 had each 80 turns. The coils were wound on bobbins of approximately .4 inch diameter. Each of the loops 5 and 6 comprised a 30 inch length of .001 inch tape, $\frac{1}{8}$ inch wide of the material known as Permalloy "C." The inductances Z_1 and Z_2 were each 32 microhenries and the condensers C_1 , C'_1 , C_2 and C'_2 were each .05 microfarad, the cut-off frequency being in the region of 3 kc./s. The carrier frequency used was 100 kc./s.

Fig. 5 shows an alternative form of magnetic amplifier for voice frequencies in which the magnetic core comprises a single spiral loop of saturable material. Carrier is applied across the terminals A_2 . The voice frequency input is at the terminals E_5 .

In the circuit shown no provision has been made for preventing induction of the fundamental carrier frequency in the winding L_5 by balancing. However, this could be done by winding the coil L_5 in two parts in such a way that the A.C. fluxes were opposed. Without this precaution the low-pass filter-section constituted by the inductances Z_5 and Z_5' and the condenser C_5 has to be designed to suppress both the fundamental carrier frequency and its harmonics. In this instance a T filter section has been chosen because a capacity low-pass filter would be equivalent to a direct shunt on the carrier supply. A small trimming condenser C_3 may be provided, adjustable to the point of maximum gain of the amplifier.

This amplifier can be conveniently constructed in a manner similar to that already described. In a particular practical case the core comprised a 30 inch length of .001 inch tape, $\frac{1}{8}$ " wide of Permalloy "C." The voice frequency winding L_5 was of 250 turns and the carrier winding L_6 was 100 turns. The inductances Z_5 and Z_5' were each 16 microhenries, the condenser C_5 was .09 microfarad, the inductance Z_6 was 32 microhenries, the condensers C_6 and C'_6 were each .045 microfarad and the resistances R_5 and R_6 were each 600 ohms. Optimum gain was achieved when the condenser C_3 was adjusted to about 1000 picofarads.

Referring to Fig. 6 a component for a magnetic switching system for voice frequencies comprises a voice frequency amplifier AMP and a carrier switch CS. The amplifier is that already described with reference to Fig. 3 modified by the inclusion of the condensers C_4 and C_7 and the inductance Z_7 , the purpose of which will be described later.

The carrier switch CS is preferably of a similar construction to that previously described for the magnetic amplifier. The coils L_9 and L_{10} have equal numbers of turns and are wound in the same direction, so that when the carrier frequency is applied at A_3 the alternating fluxes are opposed in the common limb 10 and there is no voltage induced in the windings L_7 and L_8 . However, if a direct current bias is applied across the terminals B_1 , the flux balance is upset by the field of the winding 10 L_8 and a voltage is induced in the winding L_7 .

In a particular practical case the windings L_7 and L_8 were each of 120 turns, while L_9 and L_{10} were of 80 turns. The applied carrier frequency was 50 volts R.M.S. at 50 kc./s. With the switch "on," that is with direct current bias in the winding L_8 , about 40 volts at 100 kc./s. appeared at the output of the winding L_7 . When the switch was "off," that is without direct current bias, approximately one volt appeared at the output due to imperfections in balancing. A choke was provided in 20 the direct current bias circuit to block similar voltages induced in the winding L_8 .

The output carrier voltage from the winding L_7 is fed over the lead P to the carrier windings L_3 and L_4 of the amplifier AMP.

25 The amplifier AMP functions in the way already described. When the switch CS is "on," the second harmonic output is modulated, the amplifier voice frequency being transmitted from the terminals E_2 .

As has already been mentioned, the output from the 30 switch CS in its "off" condition may be appreciable. It is therefore necessary to guard against the transmission by the amplifier AMP of a low-level signal when the switch CS is "off." For this purpose a condenser C_4 , which in the particular case mentioned above had a 35 value of .05 microfarads, was inserted between the carrier coils and the rectifier r_2 and a circuit Z_7C_7 was provided tuned to twice the carrier frequency and biased back at N to a small negative voltage, say -3 volts, sufficient to suppress this low-level signal.

40 Thus the complete circuit of Fig. 6 represents a combined amplifier and switch which will only transmit an amplified voice frequency signal when the switch CS is "on" by virtue of the application of a direct current bias at the terminal B_2 .

45 An alternative switch-amplifier could be constructed using as the amplifier AMP that of Fig. 5 instead of that of Fig. 3.

Referring to Fig. 7 switch-amplifiers of the type described above have been arranged as a selector for a 50 voice frequency switching system. The selector has one input and n outputs. Only one switch amplifier CS-AMP is shown in the drawing.

The output is selected by the application of a positive potential to the appropriate one of the n control 55 wires D_1-D_n . The voice frequency is applied through a single low-pass filter circuit F_1 common to the n switch-amplifiers. The n switch amplifiers need not then include input filters such as Z_1C_1 of Fig. 6. The common input filter F_1 is alone sufficient to obviate the appearance of carrier-frequency in the input voice-frequency circuit.

60 Application of a control potential to the control wire D_1 energises the coil L_8 (Fig. 6) of the carrier switch CS via the terminals B_1 . This causes the second harmonic of the carrier frequency to appear in the coil L_7 in the manner already described. This frequency is extended over the P lead to the winding L_3-L_4 (Fig. 6) of the amplifier AMP where it is modulated by the applied voice frequency.

65 The modulated signal is demodulated by the rectifier r_2 and filtered at Z_2C_2 and an amplified voice-frequency output appears at the terminals E_2 .

70 While a voice-frequency appears also at the inputs 75 of the remaining $n-1$ amplifiers they give no output

since in the absence of a potential on the corresponding D leads these amplifiers receive no carrier supply.

The input voice-frequency may be applied to the voice-frequency coils L_1 of the n amplifier, such as AMP, in parallel, as indicated in Fig. 7, or in series. If the series arrangement is employed the n coils L_1 may simply be connected across the voice frequency input terminals, or preferably the arrangement of Fig. 8 may be adapted. This arrangement comprises a ladder-network of which the first stage consisting of the condensers C_1 and C_1' and the inductance Z_1 constitutes a filter protecting the input circuit. The remaining stages each consists of the voice frequency winding of one of the n amplifiers together with a condenser. The n voice-frequency coils are shown at $(L_1)_1, (L_1)_2 \dots (L_1)_n$ and the corresponding n condenser at $Q_1, Q_2 \dots Q_{n-1}$. The ladder network is terminated by a resistance R_n chosen to match the impedance of the input circuit. The ladder network is then equivalent to the distortionless line, the frequency response being better than in the simple series-connected case. An element of time delay is of course introduced.

Fig. 9 shows an arrangement for a selector having n inputs and one output. In this case n switch-amplifiers of which only one CS-AMP is shown receive input signals through individual input filters. If a control potential occurs on the lead D_1 , a voice-frequency path is available from the output of AMP at E_2 through the single common output filter F_o .

While the principles of the invention have been described above in connection with specific embodiments, and particular modifications thereof, it is to be clearly understood that this description is made only by way of example and not as a limitation on the scope of the invention.

What we claim is:

In combination, a magnetic switch comprising a second-harmonic transformer having a primary, a secondary and a control winding, a magnetic amplifier comprising a second-harmonic transformer having a primary, a secondary and a control winding, means for applying a continuous alternating-current potential to the primary

25

30

40

winding of the switch transformer, means for applying a direct-current potential to the control winding of the switch transformer during selected intervals of time to cause alternating current to be induced in the secondary winding of the switch transformer during corresponding intervals of time, means for connecting the secondary winding of the amplifier transformer to the primary winding of the amplifier transformer and for transferring the said induced alternating current to the primary winding of the amplifier transformer, means for applying a continuous direct-current potential to the control winding of the amplifier transformer to cause alternating current from the primary winding thereof to be induced in the secondary winding thereof during the said intervals of time, means for applying a continuous information-bearing signal to the secondary winding of the amplifier transformer to modulate the last-said alternating current, and demodulating means connected to the primary winding of the amplifier transformer for demodulating the said modulated alternating current to obtain the information-bearing signals applied to the secondary winding of the amplifier transformer during said interval of time.
